UNITED STATES PATENT OFFICE.

WILLIAM A. THOMSON, OF DAYTON, OHIO.

DESIGN FOR A FOB OR PENDANT.

51,894.

Specification for Design.

Patented Mar. 19, 1918.

Application filed December 31, 1917. Serial No. 209,798. Term of patent 7 years.

To all whom it may concern:

Be it known that I, WILLIAM A. THOMSON, a citizen of the United States, and a resident of Dayton, in the county of Montgomery and State of Ohio, have invented a new, original, and ornamental Design for Fobs or Pendants, of which the following is a specification, reference being had to

the accompanying drawing, forming part thereof.

The figure is a plan view of the fob or pendant, illustrating my new design.

I claim:

The ornamental design for a fob or pendant, as shown.

WILLIAM A. THOMSON.
